United States Patent Office

Des. 190,770
Patented June 27, 1961

190,770

BOTTLE

Jerome Gould, Los Angeles, Calif., assignor to Louis Milani Foods, Inc., Los Angeles, Calif., a corporation of Illinois

Filed Oct. 20, 1960, Ser. No. 62,558

Term of patent 14 years

(Cl. D58—8)

FIG. 1 is a perspective view of a bottle showing my new design;

FIG. 2 is a front elevational view thereof;

FIG. 3 is a side elevational view thereof;

FIG. 4 is a top plan view thereof; and

FIG. 5 is a bottom plan view thereof.

The rear and end not shown are the mirror images of the front and side shown.

I claim:

The ornamental design for a bottle, as shown and described.
